UNITED STATES PATENT OFFICE.

HARROLD DORMAND, OF BAYONNE, NEW JERSEY.

SUCTION GAS PRODUCER FOR GASIFYING SAWDUST AND LIKE FUELS.

Application filed July 17, 1923. Serial No. 652,044.

To all whom it may concern:

Be it known that I, HARROLD DORMAND, a subject of Great Britain, now residing in Bayonne, county of Hudson, and State of New Jersey, have invented certain new and useful Improvements in Suction Gas Producers for Gasifying Sawdust and Like Fuels, of which the following is a specification.

10 This invention comprises certain improvements in suction gas producers, suitable for generating power gas by suction, and is particularly applicable to producers in which the gas is generated by sawdust or 15 other like refuse.

The invention provides simple and effective means for insuring a uniform, automatic and continuous feed of such delicate fuel into the combustion chamber, without 20 any choking in the feed, evenly distributes the fuel into the combustion chamber, thereby doing away with all poking and interfering with the combustion whilst the producer is operating, also provides simple and 25 effective means of fully maintaining the zones of combustion, thereby enriching the quality of the gas produced, prevents heavy distillation and allows the producer to successfully operate with a minimum depth of 30 fuel bed.

The invention will be understood by reference to the accompanying drawings, in which—

Fig. 1 is a sectional elevation of a gas 35 producer embodying the invention, and

Fig. 2 is a sectional plan view of the same on line 2—2, Fig. 1.

Fig. 3 is a sectional elevation of a double- 40 feed gas producer embodying the invention, and

Fig. 4 is a sectional plan view of the same on line 4—4, Fig. 3.

In a convenient embodiment of this invention, the producer is constructed with 45 outer steel casing 1 and firebrick lining 16, fire grate 3 with ash pit chamber 4 below, all sealed from the atmosphere. One or more feed bells 4 extend into the combustion chamber, the reason for plural feeds, 50 being, if used, to increase the suction area without materially increasing the height of the producer. The feed bell or bells 4 are so designed as to cause the fuel preferably sawdust to be evenly distributed over the 55 suction area, by means of a plurality of

feed apertures 4*, at, or near, the lower extremity of each feed, of rectangular or other suitable shape, and of sizes to meet existing requirements. The height of the fuel in the combustion chamber is therefore 60 regulated by the height of the apertures in the feed bell or bells. I have indicated the normal surface of the fuel by the dotted lines α , and it is this surface which I term 65 "suction area," having reference to the suction of the engine or pump withdrawing the gas through the outlets 7. The feed bells may be slightly conical in shape towards the lower part, or in other words 70 flared, to allow for the swelling of moist fuel, but not sufficiently so as to interfere with the efficient working of the apertures.

The storage hopper 5 being always maintained full, the gravitation of this column or fuel causes the same to be forced through 75 the apertures on to the suction area, whilst feeding the centre of combustion at the same time, and to prevent too heavy a flowing of fuel, after the apertures have done their work, a vacuum chamber 6 is positioned at the lower part of the storage hopper, which stays the movement, momentarily, at that point, and stops unnecessary fuel being dumped into the chamber.

It will be noted that located adjacent the 80 combustion chamber a suitable distance above the grate 3 is an annular vaporizer chamber 8, exposed to the maximum heat of the combustion zone. This vaporizer chamber is connected with an inlet 9 and a fan 10 is provided for forcing air into 85 the chamber. The chamber 8 also is connected with water feed pipes 11 so that water may be delivered in suitable quantities. The vapor produced within the 90 chamber 8 is drawn into the combustion zone, where the chemical action of gas making is going on, via vapor conduits 12 which lead from the chamber to points in the ash pit. Thus means are provided 100 whereby the zones of combustion can be maintained, and too high a temperature reduced at will, (high temperatures being detrimental to the efficient working of the producer) by the introduction of water 105 vapor, mixed with the air necessary for the gasmaking, and which is sucked into the burning mass.

An overflow pipe 13 can be used to carry away any water collecting in the va- 110

porizer, not being vaporized, therefore not necessary, on account of reduced temperature.

The admission of water vapor into the combustion zone is only necessary, when there is not sufficient moisture in the fuel being used, for the zones of combustion to maintain themselves.

The suction area must be adequately fed 10 and the suction stroke given sufficient resistance by the fresh fuel, to stop any partly carbonized fuel being drawn off with the gases, also by drawing the gases through this fresh fuel, will help to scrub out the 15 distillates.

The apertures in the feed bell, together with the vacuum chamber of the feed hopper, work automatically with the suction stroke on the producer, doing away with 20 all poking or interfering with the combustion whilst operating in the following manner:

When the suction stroke causes a suction 25 in the upper part of the combustion chamber, this suction area is immediately filled with gas, and at the same time the whole body of fuel in combustion, being so light in weight, is lifted, and immediately after falls again. After each fall the apertures 30 replenish the suction area with fresh fuel, the action of the vacuum chamber of the feed hopper arresting too heavy a fall of fuel, and this continues in automatic motion with each suction stroke.

35 It will be noted that an insulating chamber 14 surrounds the entire combustion chamber and extends to the horizontal upper wall 15 which supports the feed bell or bells 4. A vitreous lining 16 is disposed 40 intermediate the insulating chamber and the

combustion chamber and is outwardly flaring above the vaporizer chamber to restrict the combustion chamber at and below the normal surface line of greatest combustion which I have indicated by the dotted line 45 b. The vitreous lining 16 coacts with the vaporizer chamber to restrict the combustion chamber below the flaring section of the latter.

What I claim is:

A suction gas producer for gasifying sawdust and like fuels comprising a casting, a fire grate separating combustion and ash pit chambers, a feed pipe projecting into the combustion chamber and formed 50 with lateral apertures, for the passage of the fuel, a horizontal wall closing the top of the combustion chamber and affording a support for the feed pipe, an insulating lining surrounding the combustion chamber 55 and extending upwardly to said horizontal wall, an annular vaporizer surrounding the combustion chamber, means for admitting air and moisture to said vaporizer and for leading vapor therefrom to the combustion 60 chamber, and a vitreous lining intermediate the insulating lining and the combustion chamber and outwardly flaring to enlarge the combustion chamber above said vaporizer and coacting with the vaporizer to 65 restrict the combustion chamber below the flaring section.

In testimony whereof, I have signed my name to this specification in the presence of two subscribing witnesses.

HARROLD DORMAND.
